UNITED STATES PATENT OFFICE.

FRANCISCO BENDER, OF SAN FELIU DE GUIXOLS, SPAIN.

MACHINE FOR SORTING CORKS.

SPECIFICATION forming part of Letters Patent No. 746,916, dated December 15, 1903.

Application filed August 10, 1903. Serial No. 169,060. (No model.)

To all whom it may concern:

Be it known that I, FRANCISCO BENDER, of San Feliu de Guixols, Catalonia, Spain, have invented certain new and useful Improvements in Machines for Sorting Corks; and I hereby declare that the following is a full, clear, and exact description thereof, reference being had to the accompanying drawings, which form part of this specification.

10 The present invention is an improved device especially designed for assorting and selecting corks to facilitate the separation of a particular size or sizes thereof from a large number of various-sized corks; and it consists, essentially, in a reciprocating assorting-screen of novel construction which can be used alone or in connection with the known conveniently-arranged sorting-table.

15 The novel features of the invention are summarized in the claims, and the following description of the apparatus as shown in the drawings will impart a sufficiently clear understanding thereof.

In said drawings, Figure 1 is a perspective view of my novel screen in position on an assorting-table. Fig. 2 is a transverse section through Fig. 1. Fig. 3 is an enlarged plan view of the assorting-screen. Figs. 4 and 5 are enlarged top and side views of one of the 20 assorting-cones detached.

25 The assorting tray or screen frame may be of any suitable shape or size. As shown, it is rectangular and open at top and bottom, but provided at a point above its lower edge with a horizontal partition B, which is provided with a series of oval-shaped holes C, preferably arranged in longitudinal rows or series, and for convenience each series may be separated by a slight ridge or rib D, which 30 will facilitate the entrance of the corks placed in the screen into the several openings.

Below each opening C is secured an assorting-cone E, the top of which is oval to correspond with the screen-opening C, while its lower end is reduced in area and made circular, as indicated in Fig. 4. The objects of this peculiar construction of the cones are to facilitate the entrance of the corks thereinto

and to prevent any cork passing through the cones except those which are of lesser diameter than the reduced circular area of the lower end of the cone. If a cork smaller in diameter than the lower diameter of the cone falls thereinto, it will pass on through; but if a cork smaller in diameter than the oval or upper end of the cone but larger in diameter than the lower circular end of the cone drops thereinto it will be arrested, no matter whether it passes thereinto small end or large end first. The bottoms of the cones E are preferably arranged at such a distance above the lower edges of the screen-frame that the corks will not be prevented from passing through the cones by contact with the supporting-surface on which the screen-frame may rest. 55

A quantity of corks can be placed in the screen-frame and the latter held in the hands and shaken, so that the smaller corks will escape; but for convenience in operation the screen-frame A may be placed upon an operating-table E, which is provided with two hopper-shaped compartments e e'. Rollers F are arranged over hopper e, and the screen-frame can be placed thereon and easily shaken by reciprocating it back and forth upon the 60 rollers. The corks pass through the cones and escape through the hopper e into a basket or receiver placed thereunder, while any larger corks which will not pass through the cones may be dumped by turning the screen-frame upside down into the hopper e'. 65

Owing to the peculiar shape of the cones, any corks retained in the cones when the screen-frame is in its upright position over hopper e will readily disengage therefrom 70 when the screen-frame is inverted over the hopper e'. 75

In operation a quantity of unassorted corks of any ordinary kind or form are thrown into the screen-frame, which is then shaken, so 80 that the corks will be distributed into the various cones E, through which the smaller corks will pass, while large corks will be retained in the cones and frame until discharged by turning the frame upside down. 85

90 I do not limit myself to the specific form of

screen-frame herein shown, the principal novelty of the invention being the peculiarly shaped separating-cones.

Having thus described my invention, I 5 claim—

1. In a cork-separating apparatus, a screen provided with a series of oval-shaped holes and cones beneath the holes having contracted circular bottom openings.
- 10 2. A cork assorting and separating tray or screen, having a series of openings oval-shaped at their upper ends and having contracted circular lower ends.
- 15 3. A cork assorting and separating tray or screen, having a series of oval-shaped openings, and cones beneath said openings oval-shaped at their upper ends and having contracted circular lower ends.
- 20 4. A cork assorting and separating tray or screen, having a series of openings, oval-shaped at top and having contracted circu-

lar lower ends, said openings being arranged in longitudinal series, with longitudinal ribs or projections on the upper side of the screen, between the longitudinal series of openings. 25

5. A cork assorting and separating tray or screen, having a series of openings, and cones beneath said openings oval-shaped at their upper ends and having contracted circular lower ends, said openings and cones being 30 arranged in longitudinal series, with longitudinal ribs or projections on the upper side of the screen, between the longitudinal series of openings.

In testimony that I claim the foregoing as 35 my own I affix my signature in presence of two witnesses.

FRANCISCO BENDER.
